UNITED STATES PATENT OFFICE

148,602

DESIGN FOR A WAFFLE

Ken E. Bemis, Oakland, Calif.

Application July 23, 1946, Serial No. 131,868

Term of patent 14 years

(Cl. D8—1)

To all whom it may concern:

Be it known that I, Ken E. Bemis, a citizen of the United States, residing at Oakland, in the county of Alameda and State of California, have invented a new, original, and ornamental Design for Waffles, of which the following is a specification, reference being had to the accompanying drawing, forming part thereof.

Fig. 1 is a plan view of a waffle, showing my new design, both sides being identical.

Fig. 2 is a section taken longitudinally through Fig. 1.

I claim:

The ornamental design for a waffle, as shown and described.

KEN E. BEMIS.
